ATTORNEY

UNITED STATES PATENT OFFICE

WALLACE LEON LOWRY, OF JOHNSON CITY, TENNESSEE, ASSIGNOR TO AIRWAY REVOLVING SIGN COMPANY, OF JOHNSON CITY, TENNESSEE

SIGN

Application filed November 29, 1929. Serial No. 410,612.

My present invention has reference to outdoor signs.

My object is the provision of a wind actuated rotatable sign which shall be of an extremely simple nature and which includes an elongated substantially rectangular body upon whose opposite faces there is imprinted advertising matter and whose diagonally opposed ends have extensions in the nature of fins or wings that are successively engaged by air currents to rotate the body so that the advertisement on the opposed sides thereof will be successively brought to display position.

15 A further object is the provision of a sign of this character in which the body, as well as the wings or fins are made of light material and constructed in a simple but novel manner, there being brace means for holding 20 the sides of the body in proper spaced relation, a post upon which the body is mounted, anti-friction bearings between the post and body, means for constantly feeding a lubricant to the anti-friction bearings and where- 25 in the post is constructed of removably associated sections whereby the sign may be arranged at any desired elevation and also whereby the sections of the post may be readily disassociated and arranged against the 30 body for storage or for shipment.

To the attainment of the foregoing the invention consists in the improvement herein-after described and definitely claimed.

In the drawings:

35 Figure 1 is a face view of a sign in accordance with this invention.

Figure 2 is a sectional view on the line 2—2 of Figure 1.

Figure 3 is a sectional view on the line 40 3—3 of Figure 1.

Figure 4 is a detail sectional view on the line 4—4 of Figure 1.

Figure 5 is a perspective view of one of the spacer and brace members for the sign.

45 The sign is constructed wholly of metal and has its outer surface treated with a coating of paint or the like to preserve the same from the elements. The body of the sign is in the nature of an elongated and substantially rectangular hollow member. The body, in-

dicated broadly by the numeral 1, is preferably of light, thin but strong metal sheets. The body includes two face plates 2—2, respectively. These plates each have their ends flanged in opposite directions to provide the 55 ends proper for the body. These ends are indicated by the numeral 3 and, as clearly disclosed by the drawings, extend a suitable distance beyond the ends of the face plates with which they contact. The extending portions of the ends are bent over each other so that the same are substantially U-shaped in cross section, as indicated by the numeral 4, and these U-shaped portions receive therein the second and outwardly bent ends 5 of the 60 face plates 2. The parts 4 and 5 provide the diagonally opposed ends of the body with wings or fins which are contacted by currents of air for rotating the light body 1.

65 By reference to the drawings it will be noted that the wings or fins are of a less length than that of the face plates, this being provided for by slitting the inner edges and outer corners of the substantially U-shaped clamping guides for the extensions 5, and, 70 therefore, the plates proper project beyond the ends of the wings or fins a sufficient distance to be contacted by and to have bolted thereto the side flanges of the top and bottom plates 6 and 7 for the body. The flanges of 75 the top and bottom plates are substantially U-shaped in cross-section and receive the said projections of the face plates therein, as clearly disclosed by Figure 2 of the drawings.

80 The face plates 2 are held properly spaced away from each other through the medium of spacer and brace elements of a novel construction. One of these elements is best illustrated by Figure 5 of the drawings and by reference thereto it will be noted that the 85 said element comprises an angle metal member 8 that has its flanges, adjacent its ends, cut away to afford right angularly disposed projecting tongues 9, respectively, and these 90 tongues pass through suitable slots or openings in the face plates and are bent against the outer surfaces thereof. The elements 9 thus afford two right-angularly disposed shoulders 10 that are in contact with the inner surfaces of the face plates 2 and such 95 100

construction will afford a simple but ample means for preventing the buckling of the plates or sides 2 of the improvement regardless of the force of the currents of air contacting therewith.

In the top of the hollow sign 1 and at the center thereof I secure an oil or lubricant pan or receptacle 11. Lubricant is fed into the receptacle through the medium of a valve 10 closed nipple 12, similar to that employed in connection with alemite or like grease guns and the pan or reservoir 11 is designed to be filled with grease or like lubricant. If desired, the inner face of the nipple may be 15 provided with a spring influenced flat valve, although the ball valve in the nipple will evidently be found sufficient to prevent the escape of the lubricant from the pan or reservoir.

20 Fixed to the bottom of the pan or reservoir 11 there is a plate 13 provided with a central round opening, the said plate being formed with a round concavity that surrounds the opening and provides a raceway 25 for anti-friction balls 14. On these balls rests the shouldered portion 15 of a bearing sleeve 16. The bearing sleeve passes through the plate 13 and through the bottom of the pan or reservoir 11 and there is centrally 30 passed through the bearing sleeve 16 a pivot in the nature of an elongated headed bolt 17 which has its threaded end engaged by a nut. The bolt also passes through a central opening in a cap member 18 which is screwed on 35 the inner end of a tubular post section 19. By reference to Figure 2 of the drawings it will be seen that the head of the bolt does not contact with the cap member and that the nut on the bolt merely rests on the top of 40 the bearing sleeve 16. This affords a longitudinal movement of the sign on the pivot bolt 17 which will prevent the binding of the said pivot bolt should the sign be raised or lowered by the influence of wind currents.

45 The post section 19 is passed through an opening in the bottom 7 and likewise through a washer member 20 which is fixed on the inner face of the bottom 7. The outer end of the post 19 terminates only a slight distance 50 below the body 1 and is threaded and engaged by a coupling 21 which likewise has screwed therein another tubular post section 22. Obviously any desired number of post sections may be employed and it is simply 55 necessary to unscrew the couplings 21 to remove certain or all of the sections, except the sections 19 of the posts and thereby regulate the elevation of the sign or permit of 60 the post sections being arranged against the sides of the sign when the device is to be stored or shipped.

On the top 6 to the opposite sides of the nipple 12 there are arranged longitudinally 65 extending plates 23. These plates are pref-

erably scroll shape and add to the ornateness of the improvement.

Both faces or sides 2 of the sign have imprinted thereon suitable advertising indicia 70. This indicia, of course, varies in accordance with the matter to be advertised.

75 It will be apparent from the foregoing when read in connection with the drawings that I have produced a sign which is of a light construction, which is weather resisting and which will be readily revolved by air currents to display the advertising matter 24 on the opposite faces thereof. It will be further apparent that the lubricant from the pan or reservoir 11 will be fed through 80 the opening in the bottom of the pan or reservoir to the anti-friction balls 14, to constantly lubricate these elements as well as the raceways therefor. It will be further apparent that the improvement may be cheaply 85 constructed and commercialized.

90 It will be noted that by forming the fins or wings of double plates the same are materially reinforced and strengthened to prevent the bending thereof by force of air contact therewith.

95 Obviously I do not wish to be restricted to the precise details herein set forth and, therefore, hold myself entitled to make such changes therefrom as fairly fall within the 95 scope of what I claim.

Having described the invention, I claim:

1. In a sign of the class described, an elongated substantially rectangular hollow body 100 constructed of thin metal and having its diagonally opposed ends formed with projections that provide fins which are designed to be successively contacted by air currents, right angular elements comprising brace means between the face plates of the body, 105 said elements having their flanges formed with extending tongues which are received through and bent over the face plates of the body, a post comprising removable sections centrally received through the bottom of the body, an oil reservoir in the top of the body, 110 a valve controlled nipple for admitting a lubricant into the receptacle, a plate fixed on the bottom of the receptacle and having a central opening, a depression around the 115 opening providing a raceway for anti-friction balls, a bearing sleeve received through the opening and through the bottom of the plate, and having a shouldered portion affording a raceway for the said anti-friction 120 balls, a cap on the inner post section, against which the bearing sleeve rests, an elongated pivot bolt passing through the cap and through the bearing sleeve and having its 125 end engaged by a nut.

130 2. A sign of the class described, comprising an elongated substantially rectangular hollow body made up of thin metal plates, to include face plates whose ends are formed with angle extensions that afford the ends of

the body and project beyond diagonally opposed corners of the body, the said projections being arranged in lapping relation and the outer projection being slotted at its
5 juncture with the face plates and at its corners and bent over the plate contacting therewith, top and bottom plates having cross sectionally U-shaped flanges to receive therein the projecting edges of the face plates and
10 bolted thereto, spacer means between the face plates, an oil reservoir in the top of the body at the center thereof, valve controlled means for feeding a lubricant therein, a supporting post comprising removable coupled pipe
15 members, one of which is received through the bottom of the body, a washer on the bottom through which the post section passes, a cap screwed on the outer end of the said post section, a bearing sleeve providing a ball race
20 resting on the cap, a bearing plate providing a cooperating ball race fixed on the bottom of the reservoir and a longitudinally movable headed pivot passing through the cap and the bearing sleeve.

25 In testimony whereof I affix my signature.
WALLACE LEON LOWRY.
